UNITED STATES PATENT OFFICE.

JOHN FEDERKIEWICZ, OF YARDLEY, PENNSYLVANIA, AND MARCIN OLSZAK, OF TRENTON, NEW JERSEY.

COMBINED KNIFE AND WIRE-CUTTER.

1,303,277.

Specification of Letters Patent. Patented May 13, 1919.

Application filed May 10, 1918. Serial No. 233,667.

To all whom it may concern:

Be it known that I, JOHN FEDERKIEWICZ, a citizen of Poland, residing at Yardley, county of Bucks, and State of Pennsylvania; and I, MARCIN OLSZAK, a citizen of the United States, residing at Trenton, county of Mercer, and State of New Jersey, have invented certain new and useful Improvements in Combined Knives and Wire-Cutters, of which the following is a specification.

This invention relates to improvements in weapons, and particularly to types in which a knife blade having a fixed handle, is combined with a pivoted shear blade, which, acting coöperatively with the knife blade, can be used as a wire cutter.

The main object of the invention is to provide a combination implement of the type described, the parts being so arranged as to present no unsightly or unusual appearance.

Other objects are in the provision of means by which the cutter blade may be operatively extended and readily actuated without conflicting with the ordinary purposes of the knife.

These and other like objects are attained by the novel construction and combination of parts hereinafter described and shown in the accompanying drawing, forming a material part of this disclosure, and in which:

Figure 1 is a side elevational view, showing an implement made in accordance with the invention, parts being broken away in order to disclose the construction, and

Fig. 2 is a transverse, sectional view, taken on line 2—2 of Fig. 1.

The invention is very simply constructed, being comprised of two side handle elements, respectively 10 and 12, joined by screws 11 or like fastening means, those at the front being used to secure the knife blade 14, having a double beveled cutting edge 15, which extends to the point 16.

Formed between the handle elements is a recess 18, the same being curved and suited to receive the shear blade 20, the extending upper end 21 of which passes through the open recess at the back of the knife handle and is pivoted upon one of the front screws 11 in the manner shown in Fig. 1.

The lower edge of the shear blade 21, is

formed with a beveled edge 22, adapted to act coöperatively with the similar beveled edge 23, formed on the back of the knife blade 14 in an obvious manner. 55

The lower extending portion of the shear blade 20 has secured to it a plate 24, the same being adapted to be used as a contact element for the fingers in operation, and also when the shear blade is in a retracted position, 60 within the handle, to act as a cover for the recess, thereby leaving a smooth, level, lower surface for the hand, in no way interfering with its operation.

The outer end of the lever or handle element 20 has a recess 25, an outstanding lug 26 being at the extreme end, engageable with which is a detent 28, formed with a slide 29, containing an open slot 30, movable on the pin 31, set in the handle, so that the shear 70 blade handle, when inclosed within the knife handle, may be held rigidly therein, it being normally pressed out into operative position, due to the tension of a flat spring 32, held by a pin 33 within the hollow handle. 75

In operation, when the shear blade lever is in an inclosed position, within the handle, the knife may be used for any ordinary purpose that may be desired. If it be required to cut wire or the like, the slide plate 29 is 80 drawn outwardly freeing the shear blade, which is instantly pressed outwardly by the spring 32 into position for convenient operation, and, obviously when the shear blade is not required it is held in an inclosed position 85 by the sliding plate.

From the foregoing, it will be seen that a practical and essential tool has been disclosed, which is capable of continuous and effective service. 90

Having thus described our invention what we claim as new and desire to secure by Letters Patent, is—

The combination with a manually operable knife having a recessed handle, of a beveled edge formed at the back of said knife, adapted to act as one element of a wire cutter, a lever pivoted in the recess of said handle, one end of said lever acting coöperatively with the beveled edge of said knife 100 blade as a wire cutter, the opposite ends of said lever extending through the recess in

said handle, a plate secured to said lever, said plate acting as a cover for the recess when said lever is inclosed in said handle, a flat curved spring secured in said recess 5 adapted to press said lever outward, a sliding slotted and recessed detent at the end of said handle containing an open slot, and a lug formed at the extreme end of said lever

engageable with said sliding detent, whereby said lever is held when within said handle.

In testimony whereof we have affixed our signatures.

JOHN FEDERKIEWICZ.
MARCIN OLSZAK.
